UNITED STATES PATENT OFFICE.

LOGAN M. KERR, OF EBENSBURG, PENNSYLVANIA.

COMBINATION IMPLEMENT.

Application filed May 31, 1923. Serial No. 642,630.

To all whom it may concern:

Be it known that I, LOGAN M. KERR, a citizen of the United States, residing at Ebensburg, in the county of Cambria and 5 State of Pennsylvania, have invented certain new and useful Improvements in Combination Implements, of which the following is a specification.

This invention relates to combined try 10 squares, bevels, and gages, and has for one of its objects to simplify and improve the construction and increase the efficiency and utility of devices of this character.

Another object of the invention is to provide 15 a device of this character having improved means for locking the parts in adjusted position.

With these and other objects in view, the 20 invention consists in certain novel features of construction as hereinafter shown and described and then specifically pointed out in the claim, and in the drawings illustrative of the preferred embodiment of the invention.

Figures 1 and 2 are side elevations of the 25 improved instrument from opposite sides.

Fig. 3 is a transverse section on the line 3—3 of Fig. 1.

Fig. 4 is a transverse section on the line 30 4—4 of Fig. 1.

Fig. 5 is a transverse section on the line 5—5 of Fig. 2.

Fig. 6 is a transverse section of the body 35 or stock illustrating a modification of the construction.

The improved device includes a body or stock formed from a metallic strip bent into U-shape transversely, whereby spaced sides 10 and 11 and a closed bottom 12 are formed 40 as shown, and with laterally directed flanges 14 and 15 at the outer edges of the side portions.

In Figs. 1, 2, 3, 4, and 5, the side portions 45 of the body are shown reinforced by filler members 16 and 17, preferably of wood, and secured in position by clamp screws represented at 18 which pass through both the reinforcing members and likewise through both side portions of the body, as indicated 50 in Fig. 3.

A blade member comprising a straight portion 19 and a segmental portion 20 in one piece forms a part of the improved device and is provided respectively with graduations 55 to denote inches and fractions of inches

on both faces of the straight portion 19 of the blade and with degrees of a circle on one side represented in Fig. 1, and graduations to denote the "pitches" of roof rafters and the like on the other side as represented in 60 Fig. 2.

The graduations may be varied or changed as required, and it is not desired to limit the invention in any respect to any specific arrangements of the graduations. 65

The straight portion 19 corresponds in width to the depth of the stock 10—11, so that when seated within the stock, the outer edge of the portion 19 comes exactly even or flush with transverse faces of the flanges 70 14 and 15.

The sides 10 and 11 of the stock, the filler 75 members 16 and 17, and the free end of the straight portion 19 of the blade, are perforated to receive a clamp screw 21, while the blade is also perforated at the juncture of the parts 19 and 20 in alignment with corresponding perforations 26 in the sides 10 and 11 of the stock and the filler members 19 and 20, to receive a clamp bolt 22 whereby the 80 stock or blade may be locked together with the straight portion 19 "housed" within the stock.

By this means the implement forms an efficient and convenient square, the bolt 22 being threaded in the apertures in the sides 10 and 11, as shown in Fig. 4. When the implement is to be employed as a bevel or gage, the clamp bolt 22 is reversely rotated until its inner end is free from the blade, when 85 the stock can be moved with its free end over the segmental part 20 of the blade as shown in Fig. 2, and when adjusted to the required position, the members 22—23 can be utilized as a set screw to lock the stock to the segmental part of the blade, as illustrated in 90 Fig. 5.

The members 22—23 thus serve to lock the 95 blade in any required position.

When the stock is formed as shown in 100 Figs. 3, 4, 5, the straight part 19 of the blade will be provided with recesses 25 to receive the clamp screw 18 when the portion 19 is disposed within the stock, but when the stock is formed as shown in Fig. 6, the screws 105 18 and recesses 25 will not be required.

The clamp screws 21 and 22 are provided with winged heads, to enable them to be readily actuated.

The flanges 14—15 are cut away, while the 110

filler members 16, 17 when employed are likewise cut away to form a denoting edge or "pointer" indicated at 24, in Figs. 1 and 2, to enable the adjustment to be accurately made relative to the graduations.

By removing the clamp screws 21 and 22, the stock or handle may be detached, to enable the blade 19-20 to be employed as a protractor, and by releasing the clamp screw 22, the stock may be moved into a position greater than 90 degrees, if required. The aperture 26 which for the time being is free from the clamp screw 22, may be utilized to receive a pencil point or the like to 15 inscribe a segment.

The improved device can be constructed of any required size and any suitable material, and it is not desired to limit the invention to any specific material.

20 The preferred embodiment of the invention is disclosed in the drawings and set forth in the specification, but it will be understood that modifications within the scope of the claim may be made in the construction without departing from the principle 25 of the invention or sacrificing any of its advantages.

Having thus described the invention, what is claimed as new is:—

An implement of the class described comprising a straight blade and a segmental blade, said straight blade having inwardly opening recesses in spaced relation, a stock 30 formed of spaced members and pivoted at one end to opposite faces of the straight 35 blade and having threaded apertures in the free ends and movable over the segmental blade, said spaced members constituting the stock and connected by spaced pins which engage in the spaced recesses of the straight 40 blade when the members of the stock are disposed over the straight blade and limit the movement in one direction, and said straight blade and segmental blade being provided respectively with threaded sockets 45 spaced at equal distances from the pivot of the stock and at right angles to each other, and a threaded holding pin engageable alternately in the threaded apertures of the stock or against the segmental blade between the spaced sockets.

In testimony whereof, I affix my signature hereto.

LOGAN M. KERR.
